UNITED STATES PATENT OFFICE.

HENRY U. SPENCE, OF PAINESVILLE, OHIO.

INTERNAL-COMBUSTION ENGINE.

1,367,674.

Specification of Letters Patent.

Patented Feb. 8, 1921.

Application filed November 6, 1919. Serial No. 336,107.

To all whom it may concern:

Be it known that I, HENRY U. SPENCE, a citizen of the United States, residing at Painesville, in the county of Lake and State 5 of Ohio, have invented a certain new and useful Improvement in Internal-Combustion Engines, of which the following is a full, clear, and exact description.

In internal combustion engines, the oil necessary for lubricating the engaging surfaces of the cylinders and pistons is thrown into the open lower ends of the cylinders by the cranks and connecting rods when the engine is in operation; and this is true whether 15 the engine is provided with a force feed system of lubrication or a splash system of lubrication.

In commercial engines, employing either system of lubrication, as they are generally 20 constructed, more oil is delivered into each cylinder than is necessary. Engines are organized to do this on the theory, probably, that it is better to have too much than too little oil; and also because very little 25 thought seems to have been devoted to finding means for insuring the delivery of just the right quantity of oil.

So long as the cylinders and pistons are unworn and nicely fit each other no harm 30 results from the presence of this excess of oil in the engine cylinders; but, when the cylinders or pistons become worn, then the excess oil works its way up past the pistons into the combustion chamber above them 35 where it is burned. This causes the rapid deposition of carbon in the cylinders, and upon the points of the spark plugs, with results too well known to require any explanation here.

40 The usual practice for remedying this condition is to re bore the cylinder and provide a new piston and piston rings which is a very expensive method of taking care of this trouble.

45 The object of this invention is to limit and control the quantity of oil which may be thrown, in the manner stated, into the lower ends of the cylinders of such an engine; and the invention consists in an oil deflector 50 plate secured to each connecting rod over the associated crank pin; and also in the various details in the construction of the plate, and the means for connecting it in operative position as stated, all of which are shown in 55 the drawings and hereinafter described and

pointed out definitely in the appended claims.

In the drawings, Figure 1 is a transverse vertical section of the lower part of an internal combustion engine, showing only the 60 lower portion of one of the cylinders—the present invention being applied to said engine. Fig. 2 is a detached side elevation of the deflector plate in its preferred form, as shown in Fig. 1; and Fig. 3 is a bottom 65 plan view of the same plate; Fig. 4 is a vertical transverse section of the lower part of an engine with which a slightly modified form of the oil deflector is employed; and Fig. 5 is a plan view of the deflector plate 70 shown in Fig. 4.

Referring to the parts by reference characters, 10 represents the cylinder of an internal combustion engine; 12 represents the crank shaft, 14 the crank pin associated 75 with said cylinder, 15 one of the crank cheeks, and 16 the associated connecting rod. This connecting rod is of conventional form, having at its lower end a half bearing 17 which partially embraces the crank pin 14, 80 and a removable cap 18 which completes the bearing of the connecting rod upon the crank pin, said cap being secured to the lower end of the connecting rod by bolts 19.

The crank shaft and the parts thereof and 85 the lower end of the connecting rod are all inclosed within the crank case 20, which may contain associated with each crank an oil pit 21 into which a part of the lower end of the connecting rod or crank or both may dip as 90 the shaft rotates.

The foregoing is typical of the conventional construction of internal combustion engines of the splash lubrication type.

95 The lower end of the connecting rod dipping into the oil in the oil pit takes up a supply of oil, and this will be thrown by centrifugal force as the crank shaft revolves, so that much of it will go into the lower open end of the cylinder 10. As before 100 stated, the amount of oil so thrown into the cylinder is greatly in excess of that necessary for lubricating the engaging surfaces of the cylinder and piston, but so long as the piston and cylinder are nicely fitted to 105 one another this excess does no harm.

25 represents an oil deflector. It is preferably made of thin sheet metal, and has a hole 26 through which the connecting rod passes when said plate is secured in place 110

just above the associated crank pin. This plate is then fixed to the connecting rod preferably by means of the same bolts which connect the connecting rod and its cap. The 5 width of this deflector plate is substantially such that it extends almost the entire distance across the space between the two crank cheeks.

In the best form this deflector plate is so 10 connected to the connecting rod that the plate inclines upward in the direction in which the rod is moving through the upper portion of the stroke of the piston, said direction of movement being shown by the 15 arrow on Fig. 1.

When so constructed the deflector not only 20 intercepts most of the oil spray and oil drops which would otherwise be thrown into the cylinder, but it also passes at an angle 25 through the mist of oil and beats it down back toward the oil pit. This is the construction shown in Figs. 1 to 3 inclusive.

The construction shown in Figs. 4 and 5 is 30 such that the two arms of the deflector plate 25 are substantially horizontal although they have their ends turned down slightly.

The deflector plate as shown on Figs. 1 to 3 inclusive, is a piece of sheet metal having 35 a hole through it for passage of the connecting rod. This hole is produced by 40 punching from the center of the plate the tongue 27, which is left connected at one end to said plate. The tongue is then bent to the shape shown in Fig. 2, the foot of the tongue 45 being the part through which a bolt passes to fasten it to the connecting rod. The hole 50 also through the plate is formed so that the metal surrounding it lies in a horizontal plane and fits snugly upon the connecting 55 rod end.

At some point this deflector plate is split 60 from its margin to the central hole, the plate on one side of this split may be turned back enough to allow the connecting rod to pass 65 through it after which the plate may be straightened out so as to take the position 70 shown.

Having described my invention, I claim:

1. The combination with an internal 75 combustion engine having a crank case, a cyl-

inder whose lower end is in open communication with the crank case, a crank shaft mounted in said crank case, a piston in the cylinder, and a connecting rod connecting the piston and crank shaft, of an oil deflector plate which embraces and is fixed to the connecting rod close to and over the associated crank pin. 55

2. In an internal combustion engine, the combination with a connecting rod thereof, 60 of a transversely disposed oil deflector plate which embraces and is secured to the connecting rod close to and over the associated crank pin said deflector being inclined upward in the direction in which the said connecting rod moves during the upper portion 65 of the stroke of the associated piston.

3. In an internal combustion engine, the combination with a connecting rod thereof, 70 of a transversely disposed oil deflecting plate which embraces the connecting rod above the associated crank pin and is secured to the connecting rod by one or more 75 of the same bolts which secure the connecting rod to the connecting rod cap.

4. In an internal combustion engine, the combination with a connecting rod thereof, 80 of a transversely disposed oil deflector plate having a hole through which the connecting rod passes, and having integral tongues of 85 which one is longer than the other, said tongues being secured to the connecting rod by the same bolts which secure the connecting rod cap to the connecting rod.

5. In an internal combustion engine, the 85 combination with a connecting rod thereof, of a transversely extended oil deflector plate which embraces the connecting rod and is detachably secured thereto close to and over 90 the associated crank pin.

6. An attachment for an internal combustion engine comprising an oil deflector plate having through it a hole for the passage of the connecting rod and having a portion 95 adapted to be secured to the connecting rod adjacent its lower end when the plate is close to and above the associated crank pin.

In testimony whereof I hereunto affix my signature.

HENRY U. SPENCE.
